Term of patent 14 years

Int. Cl. D17—99, 03

U.S. Cl. D56—1

FIGURE 1 is a perspective view of a vibrato device for guitars, incorporating my new design;

FIGURE 2 is a top plan view thereof;

FIGURE 3 is a front elevation;

FIGURE 4 is a side elevation illustrating the side shown in FIGURE 1;

FIGURE 5 is a bottom plan view;

FIGURE 6 is a side elevation of the side not shown in FIGURE 1; and

FIGURE 7 is a rear elevation.

The dominant features of the design reside in the portions shown in solid lines.

I claim:

The ornamental design for a vibrato device for guitars, substantially as shown and described.
